Primary Examiner — Ralf Seifert(74) *Attorney, Agent, or Firm* — Andrew F. Young, Esq.; Lackenbach Siegel, LLP(57) **CLAIM**

The ornamental design for a jewelry design, as shown and described.

DESCRIPTION

FIG. 1 is a front perspective view of the present invention. FIG. 2 is a top plan view of FIG. 1.

FIG. 3 is a bottom plan view of FIG. 1.

FIG. 4 is a front elevation view of FIG. 1, the rear elevation view is a mirror image thereof; and,

FIG. 5 is a right side elevation view of FIG. 1, the left side elevation view is a mirror image thereof.

The surfaces are lightly lined for contour only.
